UNITED STATES PATENT OFFICE.

ALFRED C. ABRAMSON, OF ROCKFORD, ILLINOIS.

LAMP.

1,253,765.

Specification of Letters Patent. Patented Jan. 15, 1915.

Application filed March 6, 1917. Serial No. 152,845.

To all whom it may concern:

Be it known that I, ALFRED C. ABRAMSON, a citizen of the United States, residing at Rockford, in the county of Winnebago and State of Illinois, have invented certain new and useful Improvements in Lamps, of which the following is a specification.

This invention relates in general to the manufacture of electrically equipped devices, such for instance, as electric lamps embodying a base and a pedestal, and has more particular reference to the construction of such parts in connection with the problem of wiring the lamps.

15 In the manufacture and distribution of electric lamps, especially floor lamps, it is desirable to ship them from the factory to the dealer or user in as nearly completed and assembled condition as possible, especially 20 with regard to the electric wiring. If lamps comprising a base and pedestal as heretofore manufactured are shipped in separated or knocked-down condition, the dealer, generally unfamiliar with electrical work, must 25 employ an electrician to complete the wiring. On the other hand, if the lamps are shipped complete and ready for use each must be carefully and separately crated, which entails considerable time and expense in the 30 packing and a comparatively large cost for shipping, because of the bulky size of the crates.

The primary object of my invention, therefore, is to overcome these objectionable features by the provision of a lamp which may be shipped in knocked-down condition and yet be completely wired so that pedestals and bases may be completely arranged and crated, thereby reducing to a minimum the 40 cost of crating and shipping, and also so that the dealer or consignee may quickly and easily assemble the lamp in condition for immediate use, since the wiring is complete and requires no attention.

45 In furtherance of this general object I have provided means for detachably securing together a pedestal and a base member in an improved manner and have equipped the pedestal with the proper electric wiring including a plug connection at the supply end and have also designed the base so that the supply wire may be passed therethrough

above the floor line, all of which will be more fully described hereinafter.

Another object of my invention is to provide in connection with the above improvements, a base and pedestal of the character described so improved in construction as to be capable of being manufactured at a comparatively low cost.

60 Other objects and attendant advantages will be appreciated by those skilled in the art as the invention becomes better understood by reference to the following description when considered in connection with the accompanying drawings, in which—

Figure 1 is a side elevation of a pedestal and base of a floor lamp, equipped with electric wiring and embodying my improvements, the base and foot of the pedestal being shown in section;

Fig. 2 is a side elevation of the pedestal detached from the base;

Fig. 3 is a sectional view through the base, detached;

Fig. 4 is a plan view of the base; and

Fig. 5 is a fragmentary sectional view showing a modified form of connection between the base and pedestal.

75 My improvements are embodied in an electrically equipped device, such for example as a floor lamp of a well known type comprising a base and a pedestal mounted thereon and equipped at its upper end with a cluster of electric lamps and with a shade. It is believed that my invention will be better appreciated if a brief statement is given of the manner in which the lamps of this general character have been previously made. It has been customary to pass the 80 electric wires for the lamps longitudinally through the pedestal to the underside of the base and to pass the lower or supply end of the wires upwardly through the base at a point outside of the peripheral edge of the 85 foot of the pedestal and to provide this supply end of the wires with a suitable plug connection for attachment with an electric socket. As a consequence of this construction it was necessary to attach the plug connection to the supply end of the wires after the lamp was fully assembled, hence it was necessary to either manufacture and ship 90 the lamps complete and ready for use or if 95 100

sent in knock-down condition to complete the wiring after the dealer had assembled the lamps, both methods being unsatisfactory for reasons explained above.

- 5 Referring now to Figs. 1 to 4 inclusive, a base designated generally by reference character 6 is provided with a central aperture 7 which receives a tenon 8 of a pedestal designated generally by character 9. The pedestal carries at its upper end a cluster of electric lamp sockets 11 and is adapted to support a shade overlying the lamps, the shade being not shown since it has no connection with the present invention. The 10 electric wires for the lamp sockets 11 pass longitudinally through the pedestal, in some instances through a small pipe and in others simply through a hole bored through the pedestal. In the form shown in Fig. 1 a 15 small pipe 12 passes longitudinally through the pedestal and projects below the tenon or lower end thereof. The pipe 12 is fixedly secured to the pedestal and its lower end is exteriorly threaded and receives a nut member 20 such as a wing or thumb nut 13. With a suitable washer 14 mounted on the pipe 12 intermediate the base and thumb nut, the latter may be tightened so as to rigidly secure the base to the pedestal. The supply 25 end of the electric wiring 15 which enters the pedestal, or more specifically the pipe 12, at its lower end is equipped with a plug connection 16 for attachment with the ordinary supply socket.
- 30 My invention designs to so shape the base as to allow a pedestal completely wired, including a plug connection, to be attached to a base with the wiring passing through the base above the floor line without marring 35 the design of either the base or pedestal and allowing the same to be assembled without interference with the electric wiring. In the present instance the wiring passes through an opening 17 in the base at a point just beyond the peripheral edge of the foot of the pedestal, a suitable ferrule 18 being inserted 40 in the opening 17 to lend a finished appearance to the top of the base. The openings 7 and 17 in the base are joined by a slot 19 45 which enables the completely wired pedestal and base to be attached together for the purpose previously mentioned. This will be plainly evident by viewing Figs. 2 and 3, showing respectively the pedestal and the 50 base in the condition in which they are shipped from the factory. It will be seen that the wiring is complete and mounted on the wiring is the nut member 13, washer 14, ferrule 18 and connection plug 16. In assembling the pedestal and base, the parts 55 13 and 14, together with the portion of the wiring 15 adjacent to the pedestal are passed downwardly through the openings 7 and 19 and the tenon is inserted into the opening 7. 60 The washer 14 is then slid up into position

and the thumb nut 13 is screwed onto the lower end of the pipe 12 and tightened until the base and pedestal are rigidly secured together. The ferrule 18 is then inserted in the opening 17 and the wiring drawn taut 70 as shown in Fig. 1. It is manifest, therefore, that by constructing the pedestal and base to be detachably connected together and by wiring the pedestal complete and constructing the base so that the parts may be 75 attached together with the wiring passing through the base above the floor line and at the outer side of the pedestal, the objects prefaced above in regard to shipping and assembling lamps of this general character 80 are attained.

My improvements also include an improved base structure designed to accommodate the fastening means between the base and pedestal and to allow a most simple 85 construction so that the base may be produced at a minimum cost. For this purpose the major body of the base is formed of a comparatively flat piece turned or otherwise formed to the proper design or shape harmonizing with the pedestal. Instead of making this base piece of built up sectional form so as to give proper thickness and prevent warping I have formed it of a single 90 piece, preferably of wood, and have secured 95 to its periphery or marginal portion a metal band 21 projecting below the base such distance as to allow sufficient clearance for the fastening means or nut member 13 above the floor line. This metallic band not only enables the base to be constructed cheaper than the all wood sectional bases but prevents warping and insures against an unsteady, wobbly support.

In Fig. 5 I have shown a modified form 105 of attachment between the base and pedestal. In this, the pipe 12 is omitted and the wiring simply passes through a small bore 22 longitudinally through the pedestal. The base may be constructed similar to the base first 110 described. The wiring may also be similar to that first described with the exception just mentioned that the pipe 12 is omitted. The threaded member, however, with which the nut member co-operates to secure the base to the pedestal is secured directly to the tenon of the pedestal. It consists of a threaded tubular nipple 23 rigidly secured to a cap 24 in turn rigidly secured to the tenon 25 of the pedestal and fitted snugly in the opening 120 7 of the base so as to properly center the pedestal thereon. The electric wires pass through the nipple 23. It will be evident that this construction allows the pedestal and base to be attached together and detached similarly to the connection of the first described form.

It is believed that the foregoing conveys a clear understanding of my improvements, and it should be understood that while I 130

have shown several embodiments thereof, the details of construction might be modified and changed without departing from the spirit and scope of the invention as expressed in the appended claims.

I claim:

1. As an article of manufacture, a portable electric lamp comprising a pedestal equipped with an electric fixture and with 10 wiring therefor extending lengthwise through the pedestal and beyond the lower end thereof, a connection plug attached to this extended end of the wiring so that the lamp is completely wired and ready for use, 15 fastening means permanently but adjustably disposed on the extended end of the wiring, a base adapted for attachment to the pedestal and constructed so that the extended end of the wiring, including its connection plug, 20 will not interfere with the attachment of the base to the pedestal, said fastening means on the wiring serving to detachably secure the base to the pedestal.

2. As an article of manufacture, a portable lamp including a separable pedestal and base especially adapted to be shipped in separated or knocked-down condition, with the wiring and its connections ready for use, comprising a pedestal equipped with 25 an electric fixture and wiring therefor passing longitudinally through the pedestal and beyond the lower end thereof, a connection plug attached to the end of the wiring extending from the lower end of the pedestal 30 for connection to an electric socket, whereby the pedestal may be shipped in completely wired condition and ready for use, a base constructed for attachment to the pedestal without interfering with the wiring thereof, 35 and means for securing the base to the pedestal.

3. A lamp structure, comprising a separable pedestal and base, the pedestal being equipped with an electric fixture and wiring 40 therefor extending longitudinally through the pedestal and beyond the lower end thereof, a connection plug or the like attached to the lower end of the wiring for attachment to an electric socket, the base being shaped 45 to receive the pedestal and to provide an opening through which the wiring may be passed when assembling the base and pedestal and through which opening the connection plug wiring emanates from the base 50 above the floor line, and means for securing the base to the pedestal, whereby the base and pedestal may be shipped separate with the wiring of the pedestal complete and ready for use, and the base and pedestal 55 may be assembled without interfering with the wiring.

4. A lamp structure comprising a separable base and pedestal, the latter of which is equipped with an electric fixture and wiring 60 therefor emanating from the bottom of the

pedestal and equipped with a connection plug, the base being constructed to receive the pedestal without interfering with the complete wiring thereof, and means for securing the base to the pedestal.

70

5. In a lamp structure, the combination of a separable base and pedestal, the latter of which is equipped with an electric fixture and wiring therefor emanating from the pedestal bottom and having a connection 75 plug or the like attached to its end, and fastening means permanently and adjustably mounted on the wiring between the connection plug and the pedestal and adapted to secure the base to the pedestal, whereby the 80 pedestal, its wiring, connection plug and fastening means on the wiring may be shipped complete as an entirety, the construction including means permitting the pedestal and base to be assembled without 85 the removal or disassociation of any of the parts.

6. The combination of a pedestal equipped with an electric fixture and wiring therefor 90 extending longitudinally through the pedestal and emanating centrally from the bottom thereof, the end of this wiring being provided with a connection plug or the like, a base adapted to receive the pedestal and having a radially extending opening from 95 the center of the pedestal base to the outer edge thereof, whereby in assembling the pedestal and base the wiring emanating from the pedestal may be passed through said opening without interfering with the 100 connection plug on the wiring, and means for connecting the base to the pedestal.

7. The combination of a pedestal equipped with an electric fixture, wiring therefor 105 passing longitudinally through the pedestal and emanating from the base thereof and equipped with a connection plug or the like so that the pedestal and its wiring is complete and ready for use, a base adapted to receive the pedestal, fastening means loose 110 on the wiring between the connection plug and the pedestal so as to be permanently disposed on the wiring and adapted to co-operate with the base and pedestal for securing the same together, the structure including 115 means whereby the base and pedestal may be assembled and secured together by the fastening means on the wiring without interfering with the plug equipped wiring which emanates from the structure above the floor 120 line.

8. A lamp structure comprising a pedestal equipped with an electric fixture and wiring therefor extending lengthwise through the pedestal and emanating from the bottom 125 thereof and equipped at its end with a connection plug or the like so that the wiring is complete and ready for use, a base adapted to receive the pedestal and having a radial opening, a washer, a nut and a ferrule re- 130

spectively mounted on the wiring between the pedestal and the connection plug, and threaded means carried by the pedestal and through which the wiring passes, whereby in 5 assembling the pedestal and base the wiring may be disposed in the opening in the base without interfering with the connection plug

and the washer and nut may be operatively positioned with the nut in connection with the threaded member of the pedestal to secure the base and pedestal together, and the ferrule may be inserted in the opening in the base to lend a finished appearance thereto.

ALFRED C. ABRAMSON.
